UNITED STATES PATENT OFFICE.

JAMES H. BAKER, GEORGE F. SHEVLIN, AND FREDERICK H. BAKER, OF SARATOGA SPRINGS, NEW YORK.

VALVE FOR HYDRAULIC MOTORS.

SPECIFICATION forming part of Letters Patent No. 651,334, dated June 12, 1900.

Application filed June 27, 1898. Serial No. 684,604. (No model.)

To all whom it may concern:

Be it known that we, JAMES H. BAKER, GEORGE F. SHEVLIN, and FREDERICK H. BAKER, citizens of the United States, residing at Saratoga Springs, in the county of Saratoga and State of New York, have invented an Improvement in Valves for Hydraulic Motors, of which the following is a specification.

- Piston-valves in great varieties have been made use of for directing a fluid into a cylinder containing the piston. The present invention relates to a peculiarly constructed piston-valve adapted to admit water under pressure into one end or the other of a cylinder containing a piston the rod of which presses against a block of wood to hold the same against a revolving grinder that reduces the wood to pulp for the manufacture of paper or against some other device to be moved.
- The water made use of in paper-mills is very frequently impregnated with acid and mineral substances that are injurious to the valve and chest in the hydraulic motor, and in addition to this such valve is liable to be injured and obstructed by sedimentary or foreign substances in the water. In our present invention we make use of a cylinder, preferably of cast-iron, with a peculiar base that is adapted to be bolted to the cylinder forming the water-motor, and this valve-cylinder is open at the ends, so that it can be bored out to receive a tubular lining of brass, which may be removable, and it is perforated at the respective ports of the valve-chest, so that the perforations keep back foreign substances that might interfere with the working of the valve, and this lining can be taken out from time to time, as may be necessary in cleansing the valve and chamber, and the valve itself is in the form of a spool upon a spindle, and end disks or washers are used for confining the cup-leathers that surround the valve-stem, with their edges extending toward each other, and the water or other fluid pressure passes through a port into the spaces between the two pistons or cup-leathers, and two other ports surround the cylinder and communicate with the motor to be actuated, there being holes through the lining of the cylinder at these other ports, such holes allowing the

free passage of the water; but the lining prevents injury to the cup-leathers as they pass by the respective ports. The small holes in the lining prevent the cup-leather edges expanding into and being injured by the metal at the edges of the holes.

In the drawings, Figure 1 is a sectional plan view. Fig. 2 is a vertical section, and Fig. 3 is a diagram, illustrating the cylinder, piston-rod, and connection to the follower that presses a piece of wood against the grinder; and Fig. 4 shows our improvement as adapted to two pressures of water.

The cylinder base and ports are preferably of cast-iron, the cylinder A having end flanges 65 2 and a base A', adapted to be bolted to the side of the motor-cylinder B, and in this motor-cylinder are ports 3 and 4, extending to the respective ends, and in the surface of the base A' are channels or ports 5 and 6, extending to holes that open into the ports 7 and 8, that are in the form of annular channels around the inside of the cylinder A, and there is also an annular channel between the ports 7 and 8, forming a port 9, into which the screw-threaded openings 10 and 11 pass, and these are adapted to receive a supply-pipe for water or other liquid under pressure, so that such supply-pipe can come from either one direction or the other, the hole that is not in use 80 being closed by a screw-plug.

Within the cylinder A is the lining-sleeve C in the form of a tube, of brass or similar material, fitting tightly the inside of the cylinder A, and it is generally advantageous 85 to make this lining-sleeve sufficiently loose to allow for its removal whenever necessary to give access for cleaning the ports of the valve-chest, and around the lining-sleeve fine holes are bored at 12, 13, and 14 in annular 90 ranges or rows adjacent to the respective ports 7, 8, and 9, and the head D is secured to one end of the cylinder A and the head E to the other end, and in the head E is an opening screw-threaded to form a coupling for 95 the discharge water-pipe, and upon the head D is a stuffing-box or packing-gland 15 for the piston-rod F, the outer end of which is connected to the lever G and by a link H to the pivot-jaw I, that is screwed to the flange 100

of the cylinder, so that by the lever G the piston-rod F can be moved in one direction or the other by hand.

Within the cylinder A and lining-sleeve C 5 is the piston-valve, having a spool or body K and washers L and M, cup-leathers 17 and 18, facing each other, and a clamping-nut 19, by which the parts of the piston-valve are held together, and the length of this piston- 10 valve is such that the cup-leathers will come upon the plain portion of the lining-sleeve between ranges of holes 12 and 14 and the middle range of holes 13, so that when the piston-valve is in the intermediate position 15 the water supplied by the port and holes 13 will be retained between the cup-leathers and will not pass to either port 7 or 8; but when the piston-valve is moved in one direction 20 the water under pressure can pass through the holes 14 and port 8, and when moved in the other direction the water can pass through the holes 12 and the port 7 and according to the position of the piston-valve, 25 so that the water under pressure will reach either one end or the other of the motor-cylinder to give motion to the piston B' therein in one direction or the other and move the piston-rod B² and the follower to press the piece of wood to be ground into pulp toward the 30 grinder or the reverse or to do other work.

The port 20 extends through the metal of the cylinder-casting from one end to the other of such cylinder A, and the ends of this port 20 open through the lining-sleeve, such lining-sleeve advantageously being notched to 35 form the openings; but, if desired, numerous perforations might be provided, and the escape-water from the cylinder passes either by 7 or 8 to one end or the other of the cylinder A, and when it passes to the end of the cylinder A, near the gland 15, it goes through port 20 to the other end of the cylinder and thence to the discharge-pipe that is screwed to the head E.

45 The piston-valve constructed as aforesaid is not liable to injury, it is easily made or repaired, foreign substances that would injure the valve are excluded, the valve can be taken apart and cleaned with facility, and 50 because the pressure is balanced upon the cup-leathers the valve can be moved even under heavy pressures with but little power applied to the lever or handle, and the cup-leathers are not liable to injury by sand or 55 other foreign substances and can be easily replaced if worn out.

In Fig. 4 the present valve is represented with two sets of cup-leathers, the object being to make use of water or other fluid at two 60 different pressures, one pressure being used in returning the apparatus to a normal position and the other pressure for performing

the work. The parts heretofore described are identically the same, with the exception that the cylinder is prolonged sufficiently for 65 the reception of an annular port 30, similar to the port 9, and the lining to the cylinder is also proportionately lengthened to correspond to the length of the cylinder, and a second set of cup-leathers at 31 32 are made use of, there 70 being a second spool K' upon the elongated valve-rod F. If now a liquid is supplied to the port 9 of one pressure and to the port 30 of another pressure, there will be a liquid of a higher pressure acting at one end of the cylinder B than at the other end, and the proportion of the parts is such that the spool and cup-leathers 17 and 18 act with the inlet 9 and the port 7, leading to the port 5 at one end of the cylinder B, and the spool K' and cup-leathers 80 18 and 32 act in connection with the fluid at a different pressure from the supply pipe or port 30, passing by the port 8 at 6 to one end of the cylinder B for moving the piston and rod in such cylinder in one direction, the escape or 85 exhaust in both instances passing in the reverse direction through the holes 14 or 12 in the tubular sheet-metal lining C and by the pipe or opening 20 to the exhaust-pipe connected to the head E of the valve-chest. 90

In both cases the motion of the piston-valve is arrested in one direction by the collar or washer L engaging the interior of the head D and the collar or washer M engaging the annular seat at the inner end of the head E in 95 the other direction.

We claim as our invention—

The combination in a piston-valve with the cylinder having ports cast in the interior thereof, of a lining-tube of brass or similar 100 material perforated with ranges of numerous small holes in line with the ports, a rod, two valve-bodies around the rod, cup-leathers standing in opposite directions at the ends of the valve-bodies, and between one valve-body 105 and the next, and washers around the valve-rod and adjacent to the end cup-leathers, a clamp for holding the parts of the valve together, a lever for moving the piston-valve, a link and pivot-jaw connected to the cylinder-head and to the lever, there being hubs upon the cylinder forming couplings for a discharge-pipe and for pipes leading water at 110 two different pressures to the separate annular ports surrounding the cup-leather valves, 115 substantially as specified.

Signed by us this 2d day of June, 1898.
